CLAIM

The ornamental design for a graphical user interface for a display screen or portion thereof, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a graphical user interface for a display screen or portion thereof showing our new design;

FIG. 2 is a front view of another graphical user interface for a display screen or portion thereof showing our new design;

FIG. 3 is a front view of a graphical user interface for a display screen or portion thereof showing our new design; and,

FIG. 4 is a front view of another graphical user interface for a display screen or portion thereof showing our new design.

The broken lines in the Figures showing environment are for illustrative purposes only and form no part of the claimed design.
